G. F. READ.
WINDING MECHANISM.

(Application filed June 2, 1898.)

(No Model.)

UNITED STATES PATENT OFFICE.

GEORGE F. READ, OF NEW YORK, N. Y., ASSIGNOR TO ROBERT HOE, THEODORE H. MEAD, AND CHARLES W. CARPENTER, OF SAME PLACE.

WINDING MECHANISM.

SPECIFICATION forming part of Letters Patent No. 635,979, dated October 31, 1899.

Application filed June 2, 1898. Serial No. 682,335. (No model.)

To all whom it may concern:

Be it known that I, GEORGE F. READ, a citizen of the United States, residing at New York, county of Kings, and State of New York, have 5 invented certain new and useful Improvements in Winding Mechanism, fully described and represented in the following specification and the accompanying drawings, forming a part of the same.

10 This invention relates to improvements in winding reels or rolls.

In winding lengths of material—such as paper, cloth, and other fabrics—upon reels or rolls if the reel or roll be allowed to rotate at 15 a uniform speed constantly increasing lengths of material will be wound thereon, due to the fact that the diameter of the reel or roll is constantly increasing by reason of the accumulation of material thereon. In many instances, however, it is desirable that the 20 amount of material wound on the roll be constant for each revolution of the roll no matter what the size of the roll may be. In such cases it is usual to cause the speed of rotation of the roll to decrease as the roll increases in size, and many more or less complicated mechanisms have been produced to effect this result.

It is the object of this invention to provide 25 a roll or reel with operating devices which are simple in construction, whereby they are economical to produce and maintain, which are sure in operation, and which shall cause the amount of rotation of the roll to vary as the amount of material thereon varies, so that the amount of material wound upon the roll shall be constant.

With this object in view my invention consists in certain constructions, parts, improvements, and combinations which will be hereinafter fully described, and pointed out in the 30 claims hereunto appended.

In the accompanying drawings, which constitute a part of this specification and in which 35 like reference characters indicate same parts, Figure 1 is a side view of a winding or reeling mechanism embodying my invention. Fig. 2 is a detail view of the reel-operating devices on a larger scale than that employed in Fig. 1. Fig. 3 is an end view of the devices shown in 40 Fig. 2.

For the sake of convenience in illustration the invention is shown as applied to the winding mechanism which operates upon the wiping material used in plate-printing machines. 55 It is to be understood, however, that the application of the invention is by no means limited to plate-printing machinery, but that it may be used generally wherever it is desired to cause a winding-reel to unwind or 60 accumulate constant amounts of material.

In this the preferred form of my invention A indicates a frame which is bolted or otherwise conveniently secured to the frame of a plate-printing machine. 65

B is the wiping pad or cushion, mounted upon springs in a usual and ordinary way, the springs being indicated in dotted lines at b b'.

At one end of the frame is mounted in suitable bearings a roll or spindle, the shaft of which is marked E and the rotation of which is controlled by friction brake devices, (indicated at F.) G indicates a second roll or reel, the shaft H of which is mounted in slotted 75 bearings I at the end of the frame opposite to that in which the shaft E is mounted. The wiping-web W is drawn from the roll E and is wound upon the reel G, the slotted bearings permitting the said reel to rise as the 80 wiping-web accumulates thereon, this being indicated by the dotted-line construction in Fig. 1.

K K' indicate a pair of pull-off rollers which act to unwind the web from the reel E. The 85 roller K is operated by means of a pawl k, carried on an arm k', which operates in conjunction with the ratchet-wheel k² in a manner which will be well understood, the roll K' being operated by friction from the roll K. 90

L indicates guiding-rolls, two of which are, or may be located at each side of the frame to guide the web properly to and from the wiping pad or cushion B.

M indicates a roll suitably journaled in the 95 frame, the office of which is to guide the wiping material properly to the reel and also to assist by friction upon the reel in properly winding the material thereon. This roll M is operated by a pawl m', acting in conjunction with a ratchet-wheel m², the pawl being carried on one of the arms N' of a bell-crank 100

which is journaled on the shaft of the roll M. The other arm N of the bell-crank is connected to a rod O, which is given vertical movements by any suitable mechanism, the bell-crank being thereby oscillated. The arm N' of the bell-crank is connected by a suitable connecting-rod Q to the pawl-carrying arm k', so that the pull-off roller K and the roll M are simultaneously rotated and an equal amount.

It is important in handling the wiping material which is used on the wipers of plate-printing machines to have the material drawn taut across the face of the wiper. In order to effect this, it is necessary to wind the material tightly on the wind-up reel. If the material is not wound tightly on the wind-up reel, the slack is liable to be drawn backward from the reel, and thus to form folds or creases on the face of the wiper which interfere with its effective action. In order to insure that the winding material shall be tightly wound upon the reel G and so stretched taut across the face of the wiper, the said reel G rests against a support, which is preferably in the form of a roll M. The material to be wound preferably passes around this roll or support and between it and the reel, and the frictional contact between the roll and the reel operates to tightly wind the material on the reel.

On the shaft II of the winding-reel is mounted a slotted lever R. This slotted lever engages an operating-pin n, carried on the arm N' of the bell-crank before referred to, a snug connection, but at the same time one that permits the lever to slide on the pin, being secured by means of a screw n' and washer n'', as is clearly shown in Fig. 3. The several parts are proportioned so that when the shaft II of the reel G is at the bottom of the slots I in the frame the operating-pin n on the arm N' of the bell-crank will be substantially opposite the outer circumference of the reel G. The slotted lever R is formed with a hub or boss R³, through which passes the shaft II before referred to, the hub being secured on the shaft by means of a washer and screw. Extending upward from this hub or base is a short arm R', upon which is mounted a pin R². On this pin R² is hung a spring-pawl R³, which engages a ratchet R⁴, which is mounted on the shaft II of the reel G. It is obvious that when the slotted lever R is operated by rocking the bell-crank the reel G will be rotated in the direction of the arrow in Figs. 1 and 2. Also mounted on the shaft II and between the ratchet-wheel R⁴ and the frame is a two-armed support, one arm of which, S, carries a spring-pawl S², which acts to prevent backward movement of the ratchet-wheel R⁴, and the other arm of which, S', extends up and is bent over to form a projection S³, which extends into the slotted bearing I and locks the support against rotation.

The parts being constructed and arranged as above described, it will be understood that when the bell-crank is operated through

the rod O the rolls K and M will be simultaneously rotated and an equal amount. The roll K, operating in connection with the roll K', with which it frictionally engages, will act to pull off a given amount of web of wiping material W from the reel E, the web being led between these rolls. At the same time the reel G will be rotated by means of the slotted lever R, the pawl R³, and the ratchet-wheel R⁴, and it will turn the roll M and cause it to wind up an amount of wiping material equal to that which is pulled off from the reel E. As the wiping material accumulates upon the reel G the diameter of this reel will be increased by reason of the accumulation of web thereon, and since it rests directly upon the roll M the reel will rise or be forced up in the bearings I, carrying with it the slotted lever R. As the slotted lever R is moved upward by the reel G the pin in the bell-crank will engage it at successive points, each one of which is at a successively-increasing distance from the center of the shaft II, upon which the slotted lever is mounted. The bell-crank therefore is acting upon a lever which is practically constantly increasing in length, but the pivotal point of which remains the same, and inasmuch as the throw of the bell-crank is constant the rotative movement imparted to the reel by the slotted lever R through the operating sources will constantly decrease. Since, furthermore, the pin N on the bell-crank lever is so located that it reciprocates in a curved line which is always practically tangent to the circumference of the reel G no matter what the diameter of this reel and the material wound thereon may be the rotative movement imparted by it to the reel will vary and vary proportionately to the amount of increase in the diameter of the reel caused by the accumulation of material thereon.

It will be seen, therefore, that this device provides a reeling mechanism which is positive and sure in its action, is simple in construction, which will always act to cause the same amount of material to be taken up by the reel no matter what its diameter may be, and which will wind the material tightly upon the reel.

It is to be understood that the invention is not to be restricted to the precise means which have been herein described. Many modifications are possible, and it is to be understood that the invention includes all such modifications as are within its scope and spirit. While, furthermore, the invention is primarily intended for use as a winding-up device, it is obvious that the mechanism might with slight changes be used as an unwinding or feeding-off mechanism, and it is to be understood that such a use is contemplated.

What I claim is—

1. The combination with a reel, of a rotary support upon which the reel rests and which by reason of the weight of the reel operates in connection therewith to tightly wind the

material thereon, mechanism for giving the reel successive partial movements to vary the amount of material thereon, and means for varying the operative effect of said mechanism on the reel as the accumulation of material thereon causes the reel to vary in diameter, substantially as described.

2. The combination with a reel, of a rotary support upon which the reel rests and which 10 by reason of the weight of the reel operates in connection therewith to tightly wind the material thereon, mechanism for giving the reel successive partial movements to vary the amount of material thereon, and means 15 for automatically varying the operative effect of said mechanism as the reel varies in diameter, substantially as described.

3. The combination with a reel, of a rotary support upon which the reel rests and which 20 by reason of the weight of the reel operates in connection therewith to tightly wind the material thereon, mechanism for giving the reel successive partial rotative movements, 25 operating devices therefor having a constant throw, and means whereby the constant throw of the operating devices is caused to give varying movements to the reel-operating devices corresponding to the variations in diameter of the reel, substantially as described.

30 4. The combination with a reel, of a rotary support upon which the reel rests, means for guiding the material to be wound upon the reel around the support and between it and the reel, mechanism for giving the reel successive partial movements to vary the amount 35 of material thereon, and means for varying the operative effect of said mechanism on the reel as the amount of material thereon causes the reel to vary in diameter, substantially as 40 described.

5. The combination with a reel, of a rotary support upon which the reel rests and which by reason of the weight of the reel operates in connection therewith to tightly wind the material thereon, a pawl-and-ratchet mechanism giving the reel successive rotative movements, and means whereby the pawl-and-ratchet mechanism is automatically caused to vary its rotative effect upon the reel as the 50 accumulated material thereon causes the reel to vary in diameter, substantially as described.

6. The combination with a reel, of a rotary support upon which the reel rests and which 55 by reason of the weight of the reel operates in connection therewith to tightly wind the material thereon, bearings in which the reel is mounted and in which the position of the reel changes as the amount of material thereon varies, mechanism for giving the reel successive rotative movements, and fixed means for operating said mechanism, substantially as described.

7. The combination with a reel, of bearings 60 in which it is mounted and in which the position of the reel changes as the amount of material accumulated thereon varies, a rotary

support upon which the reel rests and which by reason of the weight of the reel operates in connection therewith to tightly wind the 70 material thereon, a mechanism including a lever for rotating the reel, and means for operating the lever, said means acting at different points in the lever, which points vary proportionately to the variations in the diameter of the reel, substantially as described. 75

8. The combination with a reel, of bearings in which it is mounted and in which the position of the reel changes as the amount of material on the reel varies, a support upon 80 which the reel rests and which by reason of the weight of the reel operates in connection therewith to tightly wind the material thereon, means for guiding the material between the support and the reel, mechanism including a lever for rotating the reel, and means for operating the lever, said means acting at different points in the lever, which points vary proportionately to the variations in the diameter of the reel, substantially as de- 85 scribed. 90

9. The combination with a reel, of bearings in which it is mounted and in which the position of the reel changes as the amount of material accumulated thereon varies, a rotary support around which the material to be wound upon the reel passes and which operates to tightly wind the material on the reel, 95 pawl - and - ratchet mechanism including a pawl-carrying lever for rotating the reel, and means for operating the lever, said means acting at different points in the lever, which points vary proportionately to the variations in the diameter of the reel, substantially as 100 described. 105

10. The combination with a reel, of a rotary support upon which the reel rests and which by reason of the weight of the reel operates in connection therewith to tightly wind the material thereon, a mechanism for rotating the reel, said mechanism including a lever and means operating at different points in the length of the lever to rotate the reel, the position of said points being determined by the changes in the diameter of the reel 110 115 due to the amount of material accumulated thereon, substantially as described.

11. The combination with a reel, of a support against which the reel rests and around which the material to be wound upon the reel passes, a mechanism for rotating the reel, 120 said mechanism including a slotted lever, a bell-crank for operating the slotted lever, said bell-crank operating at different points in the lever, which points are determined by the 125 changes in the diameter of the reel due to the material accumulated thereon, substantially as described.

12. The combination with a winding-reel, of a rotary support upon which the reel rests 130 and which by reason of the weight of the reel operates in connection therewith to tightly wind the material thereon, a pawl-and-ratchet mechanism for rotating the reel, said mech-

anism including a slotted pawl-carrying lever, a bell-crank for operating the slotted lever, said bell-crank operating at different points in the lever, which points are determined by 5 the changes in the diameter of the reel due to the material accumulated thereon, substantially as described.

13. The combination with a reel, of a rotary support upon which the reel rests and 10 which by reason of the weight of the reel operates in connection therewith to tightly wind the material thereon, a pawl - and - ratchet mechanism mounted upon the shaft of the reel, said mechanism including a slotted pawl 15 carrying lever, a fixed bell-crank, one arm of which engages the slotted lever, and means whereby the reel and slotted lever are caused to vary their position with relation to the bell-crank as the diameter of the reel and the 20 accumulated material thereon varies, substantially as described.

14. The combination with a reel, of slotted bearings in which the reel is mounted, a support upon which the reel is superposed and 25 rests whereby the reel is caused to vary its position in the bearings as the accumulated material thereon varies, and mechanism for causing the reel to be given varying rotative movements corresponding to its varying positions in the bearings, substantially as 30 described.

15. The combination with a reel, of slotted bearings in which the reel is mounted, a rotary support upon which the reel is superposed and 35 rests whereby the reel is caused to vary its position in the bearings as the accumulated material thereon varies, and mechanism for causing the reel to be given varying rotative movements corresponding to its varying 40 positions in the bearings, substantially as described.

16. The combination with a reel, of a pawl-and-ratchet mechanism for operating the same, such mechanism including a slotted 45 lever mounted upon the shaft of the reel, slotted bearings in which the reel is mounted, a roll mounted in stationary bearings and whose periphery is in contact with the periphery of the reel, means for giving the roll 50 successive rotative movements of constant length, said means acting in connection with the slotted lever to impart varying rotative movements to the reel, substantially as described.

55 17. The combination with a roll, of a bell-crank mechanism operated by the bell-crank to turn the roll, means for giving the bell-

crank a constant throw, a reel resting against the roll, slotted bearings in which the reel is mounted, and a mechanism including a slotted 60 lever for operating the reel, said slotted lever being also operated by the bell-crank, substantially as described.

18. The combination with a roll, of a bell-crank, a pawl-and-ratchet mechanism operated by the bell-crank to turn the roll, means for giving the bell-crank a constant throw, a reel resting against the roll, slotted bearings 65 in which the reel is mounted, and a pawl-and-ratchet mechanism including a slotted lever 70 for operating the reel, said slotted lever being also operated by the bell-crank, substantially as described.

19. The combination with a roll carrying a supply of material, of pull-off rollers, a winding-reel, mechanism including a slotted lever 75 for operating said winding-reel, a guiding-roll located with its surface in contact with the winding-reel, a bell-crank on the shaft of the guiding-roll, and means whereby the said 80 bell-crank is caused to simultaneously operate the pull-off rolls, the slotted lever and said guiding-roll, substantially as described.

20. In a wiping mechanism for plate-printing machines, the combination with a roll carrying a supply of wiping material, of pull-off 85 rolls, a wiping-pad, a guiding-roll, a winding-reel, pawl-and-ratchet mechanisms for operating the pull-off rolls, guiding-roll, and winding-reel, a bell-crank, and means whereby 90 the bell-crank is caused to simultaneously operate the several pawl-and-ratchet mechanisms, substantially as described.

21. In a wiping mechanism for plate-printing machines, the combination with a roll carrying a supply of wiping material, of pull-off 95 rolls, a wiping-pad, a guiding-roll mounted in stationary bearings, a winding-reel mounted in slotted bearings and with its periphery in 100 contact with the winding-reel, mechanism including a slotted lever for operating the winding-reel, a bell-crank for actuating the slotted lever, and means whereby the bell-crank is 105 caused to operate the pull-off rolls and the guiding-roll simultaneously with the slotted lever and reel, substantially as described.

In testimony whereof I have hereunto set my hand in the presence of two subscribing witnesses.
